(57) **CLAIM**

The ornamental design for a star shaped cobra clip, as shown and described.

DESCRIPTION

FIG. 1 is a perspective view of the star shaped cobra clip according to my design;

FIG. 2 is a front elevational view of my design;

FIG. 3 is a rear elevational view of my design;

FIG. 4 is a left side view of my design;

FIG. 5 is a right side view of my design;

FIG. 6 is a top plan view of my design;

FIG. 7 is a bottom view of my design; and,

FIG. 8 is a perspective view of a second embodiment of my design, wherein the left, right, top and bottom views are the same as shown in FIGS. 4-7 of the above first embodiment and the front and rear elevational views will be identical, except opposite.

The broken lines shown on the drawings are for illustrative purposes only and form no part of the claimed design.
